CONTROL OF ELECTRIC SWITCHES

Thellwell R. Coggeshall, Bala Cynwyd, Pa., assignor
or to General Electric Company, a corporation
of New York

Application November 29, 1943, Serial No. 512,179

11 Claims. (Cl. 175—294)

My invention relates to improvements in the control of electric switches and more particularly circuit breakers, and especially circuit breakers whose operating mechanisms are fluid pressure actuated and are not inherently trip-free.

Some fluid pressure actuated circuit breaker operating mechanisms are not trip-free as long as the fluid pressure actuating means is energized. This is more or less immaterial provided the circuit controlled by the circuit breaker is normal at the time the closing operation is performed. In usual operation, however, the circuit breaker is opened in response to a fault. In order to restore service, it is important that the circuit breaker be reclosed as quickly as possible. Usually, at least two reclosures are attempted. Obviously, in order to avoid damage to the circuit breaker and connected apparatus, the circuit breaker must be free to open whenever it is closed on a faulty circuit. It is, therefore, necessary that the fluid pressure operated means be so controlled as quickly to render the circuit breaker operating mechanism trip-free. Moreover, when the circuit breaker opens after closure on a fault, it should not pump, that is, reclose and open repeatedly merely because the operator has left or is holding the control switch in the closed position. That is to say, one closing operation of the control switch should effect only one closure of the circuit breaker. In other words, some thought provoking action for the operator such, for example, as reopening the control switch before another circuit breaker closing operation can be initiated is desirable in order to minimize the possibility of damage to the circuit breaker and connected apparatus.

An object of my invention is to provide an improved trip-free and pump-free control arrangement for a circuit breaker having a fluid pressure actuated operating mechanism. Another object of my invention is to provide an improved circuit breaker control arrangement for quickly deenergizing the fluid pressure actuating means either in response to the mere closing of the circuit breaker while the circuit is normal or in response to abnormal circuit conditions at the time the circuit breaker is closed. A further object of my invention is to provide an improved circuit breaker control arrangement embodying a minimum number of auxiliary relays and the like so as to expedite the deenergizing action of the fluid pressure actuating means. These and other objects of my invention will appear in more detail hereinafter.

In accordance with my invention, I provide, for a fluid pressure actuated circuit breaker, an improved trip-free and pump-free control arrangement embodying a valve operating means and control therefor for quickly deenergizing the fluid pressure actuating means when the circuit breaker is closed and regardless of the condition of the circuit at the time of closure of the circuit breaker. Further in accordance with my invention, I provide, for a fluid pressure actuated circuit breaker, an improved control arrangement whereby successive reclosures of the circuit breaker on a faulty circuit cannot be accomplished by the operator without premeditated action on his part after each reclosure.

My invention will be better understood from the following description when considered in connection with the accompanying sheet of drawings, and its scope will be pointed out in the appended claims.

In the accompanying sheet of drawings, Fig. 1 diagrammatically illustrates a switch control arrangement embodying my invention and Fig. 2 diagrammatically illustrates modification of a part of the embodiment of my invention shown in Fig. 1.

In Fig. 1 of the accompanying sheet of drawings, I have illustrated an embodiment of my invention in a control arrangement for an electric switch such as a circuit breaker 1 whose operating mechanism 2 is fluid pressure actuated to close the circuit breaker. The circuit breaker 1 is schematically illustrated as a three-pole switch which is biased to the circuit open position by suitable means indicated as a spring 3. Also, the circuit breaker is illustrated as arranged to control a circuit comprising conductors 4, 5 and 6. As shown in elevation, the operating mechanism 2 is of the roller toggle type disclosed and claimed in a copending application of Nelson H. Westervelt, Serial No. 512,185, filed concurrently herewith and assigned to the assignee of the present application. This operating mechanism comprises an operating lever 7 and an operating crank 8. The lever 7 is mounted on the stationary pivot 9 and pivotally connected at 10 to a circuit breaker operating rod 11, indicated schematically in part by the dash-dot line 11'. For actuating the lever 7 clockwise to close the circuit breaker 1, the operating crank 8 is mounted on a stationary pivot 13 and provided at its free end with a roller 14 mounted on a pin 15. The roller 14 engages the roller 16 mounted on a pin 17 in the end of the operating lever 7 opposite its attachment to the operating rod 11.

For holding the operating mechanism 2 in the switch closed position illustrated, there is provided a prop or latch 18 which, as shown, is mounted on a stationary pivot 19, and, for reduction of friction load is arranged to engage a second roller mounted on the pin 15 and similar to the roller 14. It will be obvious that the operating mechanism described is free to collapse upon a predetermined counterclockwise movement of the prop 18 and thereby to allow the opening of the circuit breaker provided there is no support or force against the roller 14 to hold it in the illustrated position when the prop 18 is moved out of holding engagement with its associated roller.

For actuating the prop 18 in the tripping direction counterclockwise as illustrated, suitable electromagnetic means comprising a winding 20 is provided. As shown, the tripping winding 20 is arranged to be energized in response to the operation of a protective relay 21 or a tripping control switch 22. The protective relay 21 is illustrated simply as an overcurrent relay connected to be energized from a current transformer 23 in the circuit conductor 4. It will be understood, of course, that any number of relays may be employed in accordance with the art of circuit protection. Also as shown, the circuit of the winding 20, which includes conductors 24 and 25, may also include the contacts 26 of a circuit breaker *a* auxiliary switch which is closed when the circuit breaker is closed and open when the circuit breaker is open.

For actuating the operating mechanism 2 to close the circuit breaker 1, I provide fluid pressure actuated means comprising a cylinder 27 within which is slidably mounted a piston 28 carrying a piston rod 29. This rod, on its upstroke under the admission of fluid under pressure beneath the piston 28, engages the roller 14 whereby to move the crank 8 clockwise until the parts of the operating mechanism 2 are positioned as shown in the drawing with the circuit breaker 1 closed. The prop 18, unless its winding 20 is energized, drops in under its associated roller to hold the circuit breaker closed after the piston rod 29 returns to its lower position. While any suitable fluid may be provided to raise the piston 28, it is usual to use air under the desired pressure in a receiver or tank 30 from which the air is supplied to the cylinder 27 through control valve means 31 embodying my invention. On the upstroke of the piston 28, suitable energy storing means, such as springs 32, are compressed to effect the down or return stroke of the piston 28 to the lower position shown. This downstroke operation follows the cutting off of the air supply by the control valve 31 so that the air in the cylinder 27 can be quickly exhausted to atmosphere through the medium of a dump valve 33 which uncovers an exhaust port 34. This dump valve is disclosed and claimed in my copending application, Serial No. 512,180, filed concurrently herewith and assigned to the assignee of the present application. In order to avoid pressure above the piston 28 on the upstroke and also to have it return freely under the bias of the springs 32, the cylinder 27 is provided with one or more suitably located ports 27'. When the control valve 31 is open, air under pressure is admitted from the receiver 30 through the valve 31 to the back of the dump valve 33. This valve 33 moves to the left against the bias of a spring 35 and closes the exhaust port 34. Coincidentally with the closing of the

dump valve 33, the air under pressure opens an admission valve 36 mounted in the head of the dump valve 33 to uncover ports therein for the admission of air to the cylinder 27. The admission valve 36 is biased to the closed position by a spring 37 which becomes so compressed that when air is subsequently exhausted from the space 41, the valve 36 quickly closes the ports in the dump valve 33, which then more effectively moves to uncover the ports 34.

In accordance with my invention, the control valve means 31 is electromagnetically actuated, and, as shown, it is of the pilot differential type embodying a pilot valve 38 and a main valve means such as a piston valve 39. Also, as shown, it includes an exhaust valve 40 for release of air to atmosphere from behind the dump valve 33 and from the delivery portion 41 of the valve body. For pressure equalization on the inlet side of the valve 31, the main valve 39 is provided with a bleed hole 42. The pilot valve 38 seats on the upper side of the main valve 39, where it is maintained closed by the entrapped pressure above it. This pilot valve is raised against the bias of suitable energy storing or valve closing means, such as a kick-off spring 43.

For opening the pilot valve 38, I provide electromagnetic means comprising an armature 44, a magnetic housing 45, a pole piece comprising magnetic elements 46, 47 and 48, and a valve opening winding 49. As illustrated, the electromagnetic means is of the plunger and solenoid type with the armature 44 suitably connected to the valve 38 as by a rod 50. In order to hold the armature 44 in the attracted position after it is moved to this position, the pole piece magnetic element 47 is, in accordance with my invention, of permanently magnetic material, examples of which are well known to the art. Thus, it may be of the permanently magnetic alloy type known as Alnico. The prevailing pressure above the valve 39 in consequence of the bleed hole 42 keeps this valve closed. However, when the pilot valve 38 is opened in response to the attraction of the armature 44, this pressure is exhausted to the low pressure space 41 and to the atmosphere through exhaust ports 40' of the exhaust valve 40. The excess of pressure is therefore shifted from above the main valve 39 to below it so that it is lifted against the bias of a spring 51 which tends to move the armature 44 to the unattracted position. Simultaneously with the opening of the main valve 39, the exhaust valve 40, which is held open by the main valve 39 pressing on the hollow stem 52 of the valve 40 against the bias of a spring 53, is permitted to close and thus seal the outlet or delivery portion 41 of the control valve 31 against loss to atmosphere. The hollow stem 52 of the exhaust valve 40 is provided with one or more equalizing exhaust ports 54 and an uplift piston 55.

For closing the circuit breaker 1, I provide, in accordance with my invention, a closing control circuit for the valve opening winding 49. As shown, this circuit includes a closing control switch 56, the contacts 57 of a minimum pressure switch 58 which opens when the pressure in the tank 30 falls below a predetermined minimum value, a conductor 59, *b* auxiliary switch contacts 60 of the circuit breaker 1, a conductor 61, the contacts 62 of a short time delay circuit opening relay 63 whose winding 64 is energized upon closure of the closing control switch 56, a conductor 65, the valve opening winding 49,

and a conductor 66. The opening of the circuit breaker closing control circuit by the slightly delayed contacts 62 of the relay 63 insures a positive opening of the control valve 31 in response to the energization of its winding 49 and also prevents reclosure of the circuit breaker as long as the control switch 56 is kept closed. In other words, with a single closure of the control switch 56, only one closure of the circuit breaker 1 can be effected.

In accordance with my invention, I provide means for quickly returning the piston 28 to the down position shown because the circuit breaker mechanism 2, although of itself inherently trip-free, cannot move to the open circuit position as long as air pressure below the piston 28 keeps the piston rod 29 pressing against roller 14 with enough force to maintain the mechanism 2 with its parts positioned as shown in the drawing. For this purpose, I provide means for effecting the closure of the valve means 31 to cut off the pressure supply at the end of the piston stroke when the circuit breaker 1 is fully closed. As shown, this means comprises a valve closing winding 67 so wound and connected to be energized that its polarity is opposite to the polarity of the opening winding 49 and is such as to neutralize the holding flux of the permanent magnet 47 whereby to release the plunger 44 for the valve closing movement. In order to insure the energization of the valve closing winding 67 at the proper moment, the circuit of this winding is controlled by a limit switch 68 which is actuated to the closed position in response to the movement of the piston 28 so as to close its contacts 69 in the circuit of the winding 67 when the breaker is fully closed. As shown, the circuit of the valve closing winding 67 includes the contacts 69 of the cutoff or limit switch 68, the conductor 70, and the valve closing winding 67.

Also in accordance with my invention, in order to insure a fast or earlier opening of the circuit breaker 1 when it is closed during an abnormal circuit condition, I provide means for substantially simultaneously tripping the circuit breaker and effecting the closing of the valve means 31. As shown, this means comprises a valve closing winding 71 which is independent of the winding 67 and which is wound and connected to be energized to have a polarity such as to neutralize the magnetic holding effect of the permanent magnet 47 whereby to release the plunger 44 to close the valve 31 and the trip circuit comprising the tripping winding 20 of the circuit breaker mechanism. The circuit for the closing winding 71 includes the contacts of the protective relay 21 and the trip switch 22 in parallel, the conductor 24, the circuit breaker *a* auxiliary switch contacts 26, a conductor 72, and the valve closing or neutralizing winding 71.

Assuming the parts as positioned in the drawing, then when closure of the contacts of the relay 21 or the control switch 22 is effected, the circuit of the trip coil 20 is energized to move the latch 18 to the releasing position. The circuit breaker 1 is then opened by the bias of the spring 3. The circuit breaker is, of course, free to open without opposition from the piston 28 which returned to its lower position at the end of the preceding closing operation. At the same time that the trip coil 20 is energized, the valve closing winding 71 is also energized, but since the valve 39 is already closed, nothing happens at this time in consequence of this energization.

Upon the opening of the circuit breaker, the *a*

auxiliary switch contacts 26 are opened and the *b* auxiliary switch contacts 60 are closed. When it is desired to close the circuit breaker, the control switch 56 is closed, and if the pressure in the tank 30 is sufficient to maintain the low pressure interlock switch contacts 57 closed, then the circuit of the opening winding 49 is completed and will be maintained until the short time delay circuit opening relay 63 opens its contacts 62. Upon energization of the valve opening winding 49, the armature 44 is moved to the attracted position. During this movement it opens the pilot valve 38 and thereby exhausts pressure to air by way of the outlet portion 41 and the ports 40' of the valve 31 and thus effects the opening of the main valve 39 and the closing of the exhaust valve 40. Admission of air under pressure back of the dump valve 33 seats this valve against the bias of the spring 35 whereupon its associated admission valve 36 is opened against the bias of its spring 37. This admits air under pressure below the piston 28, which is thus caused to travel upward against the bias of the spring 32 to engage the roller 14 and the crank 8 and thereby turn this crank and the operating lever 17 clockwise until the prop latch 18 is free to fall under the roller and maintain the circuit breaker 1 in the closed position.

As soon as the piston 28 reaches the end of its upstroke with the breaker fully closed, the limit switch 68 closes its contacts 69 thereby completing the circuit of the valve closing or neutralizing winding 67. With the neutralization of the holding effect of the permanent magnet 47, the plunger armature 44 is rapidly actuated under the bias of springs 43 and 51 to the unattracted position to effect the closing of the pilot valve 38 and the main valve 39 whereby to shut off the supply of air to the cylinder 27. At the same time, the exhaust valve 40 is opened and the pressure back of the dump valve 33 relieved so that this valve can open under the bias of its spring 35 to dump the air in the cylinder through exhaust port 34. With the quick release of the piston rod 29 from its holding position under the roller 14, the circuit breaker operating mechanism is restored to its inherently trip-free condition.

If the breaker is closed on a faulty circuit, the operation of a protective relay, such as the over-current relay 21, or other tripping means, such as the switch 22, is immediately effective to cause the opening of the circuit breaker. In fact, if during the closing operation, current above the pick-up value of the relay 21 flows in the circuit 4, 5, 6 upon the initial touching of the circuit breaker contacts before the operating mechanism is fully latched, the completion of the circuit of the neutralizing closing winding 71 by the closing of the contacts of the relay 21 is effective to cause the closing of the valve means 31 somewhat in advance of the operation of the limit switch which controls the closing winding 67. It will accordingly be clear that the circuit breaker operating mechanism is maintained in its inherently trip-free operating condition except for the brief time necessary to effect the closing of the valve means 31 while the piston rod 29 is in contact with the roller 14 in its upper or closing position. Moreover, since the tripping or closing action of the valve means 31 is effected without the action of auxiliary relays, the closing time of this valve means is very short.

In automatic station applications, and also when the control switch 56 is of the stay-put

type, it may be desirable to have the energization of the short time delay relay 63 controlled independently of the minimum pressure switch 58, as shown, for example, in Fig. 2. In this figure, the energizing circuit of the relay 63 includes the control switch 56 and a conductor 59' without passing through the contacts 51 of the minimum pressure switch 58. With this arrangement, it will be clear that if the control switch 56 is closed when the minimum pressure switch 58 is open, the relay 63 will be energized to open its contacts 62 and will remain energized with these contacts open as long as the control switch 56 is left closed. Then, if the control switch 56 is closed and left closed while the minimum pressure switch is open, mere subsequent return of pressure cannot effect a closing operation of the circuit breaker, which might happen at an inadvertent time to cause damage or even loss of life to operating personnel.

While I have shown and described my invention in considerable detail, I do not desire to be limited to the exact arrangements shown, but seek to cover in the appended claims all those modifications that fall within the true spirit and scope of my invention.

What I claim as new and desire to secure by Letters Patent of the United States is:

1. In a control arrangement for an electric switch provided with fluid pressure actuated closing means arranged to be energized through electromagnetically actuated valve means from a source of fluid under pressure, a control circuit for effecting the opening of said valve means, a control switch in said circuit, means connected to be energized upon closure of said control switch for opening said control circuit a predetermined time thereafter, magnetic means for holding said valve means open, electromagnetic means for neutralizing the effect of said holding means, and means for effecting the energization of said neutralizing means during the closing of said electric switch.

2. In a control arrangement for an electric switch provided with means for holding the switch closed and also with a fluid pressure actuated closing means arranged to be energized through electromagnetically actuated valve means from a source of fluid under pressure, a control circuit for effecting the opening of said valve means, a control switch in said circuit, means connected to be energized upon closure of said control switch for opening said control circuit a predetermined time thereafter, magnetic means for holding said valve means open, electromagnetic means for neutralizing the effect of said valve holding means, means dependent on the completion of the action of the fluid pressure actuated means for effecting the energization of said neutralizing means, and means for substantially simultaneously effecting the energization of said neutralizing means and the release of said switch holding means.

3. In a control arrangement for an electric switch provided with means for holding the switch closed and also with a fluid pressure actuated closing means arranged to be energized from a source of fluid under pressure, means for controlling the flow of fluid from said source to said actuated means and from said actuated means comprising an electromagnetically actuated valve provided with an armature movable to the attracted position to open the valve, energizing winding means for effecting movement of the armature to the attracted position, magnetic

means for holding the armature in the attracted position, winding means for neutralizing the holding effect of said magnetic means, a control switch, a control circuit including said control switch and said energizing winding means, a time delay circuit opening relay having its contacts in said control circuit and an actuating winding connected to be energized upon closure of the control switch, and means dependent on the completion of the action of the fluid pressure actuated means for effecting the energization of said neutralizing winding means.

4. In a control arrangement for an electric switch provided with means for holding the switch closed and also with a fluid pressure actuated closing means arranged to be energized from a source of fluid under pressure, means for controlling the flow of fluid from said source to said actuated means and from said actuated means comprising an electromagnetically actuated valve provided with an armature movable to the attracted position to open the valve, energizing winding means for effecting movement of the armature to the attracted position, magnetic means for holding the armature in the attracted position, winding means for neutralizing the holding effect of said magnetic means, a control switch, a control circuit including said control switch and said energizing winding means, a time delay circuit opening relay having its contacts in said control circuit and an actuating winding connected to be energized upon closure of the control switch, means dependent on the completion of the action of the fluid pressure actuated means for effecting the energization of said neutralizing winding means, and means for substantially simultaneously effecting the energization of said neutralizing winding means and the release of said switch holding means.

5. In trip-free and pump-free control arrangement for an electric circuit breaker provided with pneumatically actuated closing means arranged to be energized from a source of air under pressure, means for controlling the flow of air from said source to said actuated means and from the actuated means to atmosphere comprising an electromagnetically actuated valve provided with an armature movable to the attracted position to open the valve, a valve opening winding operative when energized to effect movement of the armature to the attracted position, a permanent magnet for holding the armature in the attracted position, a valve closing winding operative when energized to neutralize the holding effect of said permanent magnet, a control switch, a control circuit including said control switch and said valve opening winding, a time delay circuit opening relay having its contacts in said control circuit and an actuating winding connected to be energized upon closure of the control switch, and means dependent on the completion of the action of the pneumatically actuated means for effecting the energization of said valve closing winding.

6. In trip-free and pump-free control arrangement for an electric circuit breaker provided with fluid pressure actuated closing means arranged to be energized from a source of fluid under pressure, means for controlling the flow of fluid from said source to said actuated means and from said actuated means comprising an electromagnetically actuated valve provided with an armature movable to the attracted position to open the valve, a winding operative when en-

ergized to effect movement of the armature to the attracted position, magnetic means for holding the armature in the attracted position, winding means operative when energized to neutralize the holding effect of said magnetic means, a control switch, a control circuit including said control switch and said operating winding, a time delay circuit opening relay having its contacts in said control circuit and an actuating winding connected to be energized upon closure of the control switch, means dependent on the completion of the action of the fluid pressure actuated means for effecting the energization of said winding means, and means for substantially simultaneously tripping the circuit breaker and effecting the energization of said winding means.

7. In trip-free and pump-free control arrangement for an electric circuit breaker provided with pneumatically actuated closing means arranged to be energized from a source of air under pressure, means for controlling the flow of air from said source to said actuated means and from the actuated means to atmosphere comprising an electromagnetically actuated valve provided with an armature movable to the attracted position to open the valve, a valve opening winding operative when energized to effect movement of the armature to the attracted position, a permanent magnet for holding the armature in the attracted position, valve closing winding means operative when energized to neutralize the holding effect of said permanent magnet, a control switch, a control circuit including said control switch and said valve opening winding, a time delay circuit opening relay having its contacts in said control circuit and an actuating winding connected to be energized upon closure of the control switch, means dependent on the completion of the action of the pneumatically actuated means for effecting the energization of said valve closing winding means, and means for substantially simultaneously tripping the circuit breaker and effecting the energization of said valve closing winding means.

8. In a control arrangement for an electric switch provided with fluid pressure actuated closing means arranged to be energized from a source of fluid under pressure, valve means comprising a member movable in one direction to a predetermined position to control the flow of fluid from said source to said actuated means and in the opposite direction from said position to control the flow of fluid from said actuated means, means for effecting the movement of said member in said one direction to said predetermined position, means tending to move said member in the opposite direction, means for holding said member in said predetermined position against the effect of said motion tending means, and means for neutralizing the effect of said holding means during the closing operation of said electric switch.

9. In a control arrangement for an electric

switch provided with means for holding the switch closed and also with fluid pressure actuated closing means arranged to be energized from a source of fluid under pressure, valve means comprising a member movable in one direction to a predetermined position to control the flow of fluid from said source to said actuated means and in the opposite direction from said position to control the flow of fluid from said actuated means, means for effecting the movement of said member in said one direction to said predetermined position, means tending to move said member in the opposite direction, means for holding said member in said predetermined position against the effect of said motion tending means, means for neutralizing the effect of said holding means during the closing operation of said electric switch, and means for substantially simultaneously neutralizing the effect of said member holding means and the release of said switch holding means.

10. In a control arrangement for an electric switch provided with fluid pressure actuated closing means arranged to be energized from a source of fluid under pressure, electromagnetically actuated valve means comprising an armature movable to the attracted position to control the flow of fluid from said source to said fluid pressure actuated means and to the unattracted position to control the flow of fluid from said fluid pressure actuated means, a control circuit for effecting the energization of said electromagnetically actuated valve means to move said armature to the attracted position, a control switch in said control circuit, means connected to be energized upon closure of said control switch for subsequently opening said control circuit, means tending to move the armature to the unattracted position, magnetic means for holding the armature in the attracted position after the opening of the control circuit, magnetic means for neutralizing the effect of said holding means, and means for effecting the energization of said neutralizing means during the closing of said electric switch.

11. In a control arrangement for an electric switch provided with fluid pressure actuated closing means arranged to be energized through electromagnetically actuated valve means from a source of fluid under pressure; a control circuit for effecting the opening of said valve means, a control switch in said circuit, means connected to be energized upon closure of said control switch for opening said control circuit at predetermined time thereafter, magnetic means for holding said valve means open, electromagnetic means for neutralizing the effect of said holding means, and means for effecting the energization of said neutralizing means within the region of the closed position of said fluid pressure actuated closing means.

THELLWELL R. COGGESHALL.
